UNITED STATES PATENT OFFICE.

OTTO W. MIELENZ, OF PHILADELPHIA, PENNSYLVANIA.

BASEMENT DOOR.

Application filed January 7, 1926. Serial No. 79,852.

The present invention relates to a basement or cellar door and more particularly to the type for use on sidewalks, and aims to provide a novel and improved device of this character which when in a closed position will lie flush with the sidewalk or floor, thus eliminating upstanding obstruction and the danger of anyone stumbling while walking thereover to a great extent.

Another object of the invention is the provision of means for attaching the doors to the frame so that all hinge connections are arranged under the doors and constructed in such a manner as to hold the doors in an opened position when desired.

It is also an object of the invention to provide a device of the above indicated character, which is simple and substantial in construction, which can be manufactured economically, and which will be thoroughly efficient and practical in use.

With the foregoing and other objects in view, which will be apparent as the description proceeds, the invention resides in the construction and arrangement of parts as hereinafter described and claimed, it being understood that changes can be made within the scope of what is claimed, without departing from the spirit of the invention.

The invention is illustrated in the accompanying drawings, wherein:

Figure 1 is a plan view of my improved device,

Figure 2 is a fragmentary vertical section taken on line 2-2 of Figure 1,

Figure 3 is a fragmentary plan showing the door removed,

Figure 4 is a view similar to Figure 2 but showing the door in an open position,

Figure 5 is a perspective view of one of the corner reinforcing members,

Figure 6 is a fragmentary vertical section taken on line 6-6 of Figure 7, showing the frame of the door constructed of channel iron,

Figure 7 is a fragmentary top plan of the form of my invention illustrated in Figure 6, showing the door removed, and

Figure 8 is a vertical section taken on line 8-8 of Figure 7, but showing the door in a raised position.

In carrying out the invention, the numeral 10 designates a frame, which is constructed of angle iron and arranged to ex-

tend around an opening in a floor or sidewalk. On the upper angled portions of the angle irons are secured, by means of rivets or the like, plates 11, which are of less width than the upper angled portions of the angle irons so that the inner edges thereof terminate short of the inner edges of the angle iron for providing seats or shoulders 12 which the edges of the doors 13 rest upon. The corners of the angle irons are attached together and reinforced by angled corner members 14, which are secured to the angle irons 10 in any well known manner, such as riveting or the like. The angled members 14 have relatively short side portions 15 and relatively long side portions 16, each of said relatively long side portions 16 being provided with an offset, upstanding lug 17, said lugs 17 being offset so as to extend inwardly and away from the angled members 10 the side portions 16 are secured to. 70 Pivots connected to the offset, upstanding lug 17 at each corner of the frame, by means of rivets or bolts 18, is one end of levers 19, which have their opposite ends extending towards the corners and pivots 75 connected to depending brackets 20, as at 21, carried by the door sections.

To each of the side portions 16 of each corner bracket is pivotally connected, as at 21^a, intermediate the ends of said side portions, one end of another lever or bar 22. The opposite ends of the levers or bars 22 have pins 23 provided thereon which are slidably mounted in slots 24 arranged in depending brackets 25 carried by the door sections. The levers or bars 22 are positioned adjacent the side portions 16 of the corner angled members 14 and arranged between the levers 19 and said side portions 16 so as to form a compact structure. On 90 each of the levers or bars 22 is arranged a pin 26 which is slidably mounted in a slot 27 provided in each of the levers 19.

By referring to Figure 4, it will be noted that the slots 24 in the brackets 25 and the slots 27 in the levers 19 terminate at points for limiting movement of the pins 23 and 26 respectively therein for holding the doors 13 in open position, with edges of the doors resting on the shoulders or seats formed on the angled members 10.

The door sections 13 are arranged so that each door covers one-half of the opening

and each door is pivotally connected at two corners of the frame. The doors may be locked in a closed position by means of a sliding bolt 28 carried by one of the door sections for engagement into the side of the frame and a lock 29 for locking the two doors together. As usual, a cross or reinforcing member 30 is carried by one door and has a longitudinal portion thereof offset for providing a shoulder or rest for the other door. When my improved device is arranged in a sidewalk or floor, the sidewalk or flooring is brought flush with the top surface of the plates or strips 11, which in turn are flush with the doors, thus presenting a smooth and unobstructed surface.

In Figures 6, 7, and 8 of the official drawings, I have shown a channel iron frame, such as designated by the numeral 31, said channel iron having the ends thereof received in corner channeled members 31^a and secured thereto, as at 31^b. The outer side portions of the corner channel members 31^a extend slightly above the side portions of the channel irons 31, substantially the thickness of the doors 13, and lie flush with the sidewalk or floor, so that the doors 13 resting upon the upper edges of the channel irons 31 will lie flush with the sidewalk or floor and the outer side of the corner channel members 31^a. It will be noted that by constructing the frame of the device of channel iron that the same will provide gutters for carrying off water, thus providing a water-tight door for cellars, airways, and the like. In this form of my invention, the outer portion of each channel iron is bent inwardly, as at 32, for providing the lugs to which one end of each lever 22 is pivotally connected, while the upstanding lugs 17 are mounted in the channel irons 31, as at 33. It is to be noted that when constructing the frame of channel iron that the mechanisms for connecting the doors 13 to the frame are positioned in the channel irons and not in the doorway so as to form a compact structure and eliminate danger of breaking said mechanisms when raising or lowering objects through the doorway.

When the meeting edges or sides of the doors are raised upwardly, the levers 22 are swung on their pivots 21^a, causing the pins 26 carried by said levers 22 to raise the levers 19 on their pivots 18, as said pins 26 move in the slots 27 of the levers 19, thus slightly raising the edges of the doors opposite to those that meet. Upon continual raising of the meeting edges of the doors, said doors may be swung to a position as indicated in Figure 4 of the official drawings, that is, until the pins 23 engage the ends of the slots 24 in the brackets 25, at which time the edges of the doors which have been slightly raised are brought back to engage the shoulder 12 formed on the frame, as

also clearly shown in Figure 4 of the official drawings, which will hold the doors in raised or open position.

Having thus described my invention, what I claim as new is:

1. In combination with a door opening having a frame arranged therearound, of a door, a pair of levers arranged at two corners of said frame, one of said levers of each pair having one end thereof pivotally connected to said door while the other lever has one end thereof pivotally connected to said frame, means for slidably connecting said levers together, means slidably connecting said levers pivotally connected to said frame to said door at the ends thereof opposite to that connected to said frame, and means pivotally connecting the ends of said levers pivotally connected to said door to said frame at their other ends.

2. In combination with a door opening having a frame arranged thereabout, a pair of doors arranged for closing said opening and arranged with side edges thereof engaging each other, a pair of levers arranged at each corner of said frame, one of each pair having one end thereof pivotally connected to a door while the opposite end thereof is pivotally connected to said frame, means for pivotally connecting the other of said levers to said frame at one end thereof and slidably connecting the other ends of said other levers to said doors, and means slidably connecting said levers together.

3. In combination with a door opening having a frame arranged thereabout, of a door, a bracket carried by said door adjacent each end thereof, brackets carried by said frame, levers having the opposite ends pivotally connected in said brackets carried by said frame and door and having slots arranged therein, other brackets carried by said door and having slots therein and spaced from said first mentioned brackets, other levers each having one end thereof pivotally connected to said frame adjacent said first mentioned brackets carried by said door, and a pair of pins carried by each of said second mentioned levers and being slidably received in said slots in said first mentioned levers and in said slots of said last mentioned brackets carried by said door.

4. In combination with a door opening having a frame arranged therearound, of a door, a pair of levers arranged at each side of said doors and adjacent corners of said frame, said levers of each pair being arranged to lie side by side when the door is in a closed position, means for pivotally connecting one end of one lever of each pair to said door, means for pivotally connecting the opposite ends of said levers pivotally connected to said door to said frame, said levers being pivotally connected to said door and frame having slots arranged therein,

means for pivotally connecting the other of said levers to said frame, pins carried by the other of said levers and received in the slots of said levers pivotally connected to 5 said door and frame, and means for slidably connecting said levers carrying said pins to said door.

5. In combination with a door opening having a frame arranged therearound, of 10 corner brackets secured to said frame and each having an offset, upstanding lug, a pair of doors arranged for closing said opening and having the marginal edges thereof resting on said frame or in engagement with 15 each other when the doors are in a closed position, a pair of levers arranged at each corner of said frame, one of said levers of each pair having one end thereof pivotally connected to one of said doors while the opposite end thereof is pivotally connected to 20 one of said offset, upstanding lugs, said levers pivotally connected to said lugs and doors having slots arranged therein, the other of said levers being pivotally connected at one end to said frame while the opposite end thereof is slidably connected to 25 said doors, and pins carried by said levers slidably connected to said doors for engaging in said slots in said first mentioned levers for slidably connecting said levers of each pair together.

6. In combination with a door opening

having a frame arranged thereabout, of strips secured to said frame and having the inner edges thereof slightly spaced from the 35 inner edges of said frame, angled corner brackets secured to said frame at the corners thereof, doors arranged for closing said opening and having the marginal edges thereof in engagement with said strips and 40 resting upon said frame, said doors being of substantially the same thickness as said strips so as to lie flush therewith, and levers pivotally connected to said doors and frame for imparting a raising motion of the doors 45 to an elevation above said strips prior to the swinging of said doors to open positions.

7. In combination with a door opening having a frame arranged thereabout, of 50 doors arranged for closing said opening, said frame having seat portions arranged therearound for receiving marginal edges of said doors so that the upper surface of said doors lie flush with said frame, levers pivotally connected to said doors and to said frame 55 for imparting a raising of the entire doors as the same are swung to open position, said levers being so arranged that edges of said doors will rest in the seats formed in said frame for holding said doors in open position.

In testimony whereof, I have affixed my signature.

OTTO W. MIELENZ.
